(57) **CLAIM**

The ornamental design for a transfer paper as shown and described.

DESCRIPTION

The patent or application file contains at least one drawing executed in color. Copies of this patent or patent application publication with color drawing(s) will be provided by the Office upon request and payment of the necessary fee. The sole FIGURE is a front view of a transfer paper showing our new design.

The dash-dot broken lines shown in the drawings represent the boundary of the claimed design of the transfer paper, and form no part of the claimed design. The dot-dot broken lines in the drawings form no part of the claimed design. The KMI forming no part of the claimed design is a trademark of KOREA MEDICAL INSTITUTE.
